UNITED STATES PATENT OFFICE

152,864

DESIGN FOR A TOY CHAIN

Ernest G. D. Carlson, Savannah, N. Y.

Application May 27, 1947, Serial No. 139,298

Term of patent 14 years

(Cl. D34—15)

To all whom it may concern:

Be it known that I, Ernest G. D. Carlson, a citizen of the United States, residing at Savannah, in the county of Wayne and State of New York, have invented a new, original, and ornamental Design for a Toy Chain, of which the following is a specification, reference being had to the accompanying drawing, forming part thereof.

Figure 1 is a plan view of a toy chain, showing my new design and illustrating the same in an extended position, and

Figure 2 is a side elevational view thereof in a hanging position.

I claim:

The ornamental design for a toy chain, as shown.

ERNEST G. D. CARLSON.
